UNITED STATES PATENT OFFICE.

HARRY W. STERTZBACH, OF COLUMBUS, OHIO, ASSIGNOR TO THE BUCKEYE STEEL
CASTINGS COMPANY, OF COLUMBUS, OHIO.

CAR-TRUCK BOLSTER CONSTRUCTION.

Original application filed January 11, 1927, Serial No. 160,434. Divided and this application filed
December 1, 1927. Serial No. 237,016.

This invention relates to improvements in car truck bolster constructions,—this application being a division of application for patent filed by me on the 11th day of January 5 1927, and designated by Serial No. 160,434.

One object of my present invention is to provide a bolster in which corner stresses incident to bolsters having a rectangular box-like cross section are reduced and to this end 10 to so construct the bolster that its tension member shall be tapering from its central portion to its ends and have an arcuate cross section with a curvature of substantially constant radius, from end to end, and to provide 15 such a tapering bolster construction at its outer ends with spring seat members having horizontal under faces.

With this and other objects in view, the invention consists in certain novel features of 20 construction and combinations of parts as hereinafter set forth and pointed out in the claims.

In the accompanying drawings;

Figure 1 is a side elevation of a portion of 25 a bolster embodying my improvements;

Figure 2 is a transverse section on the line 2—2 of Fig. 1;

Figure 3 is a transverse section on the line 3—3 of Fig. 1;

Figure 4 is a transverse sectional view 30 illustrating another embodiment of the invention;

Figure 5 is a transverse sectional view illustrating another embodiment of the invention, 35 and

Figure 6 is a view in side elevation of the embodiment of the invention shown in Fig. 5.

The bolster 1 is made tapering from its central portion to its ends and in the embodiment 40 of the invention shown in Figs. 1 to 3, it is made with an integral flat top web 2 which will accommodate attachments and bearings such as may be necessary on the upper side of the bolster, and between said top web and the 45 bottom of the tension member 3, an integral strengthening web 4 may be located.

The tension member 3 of the bolster is arcuate in cross section and this arcuate form is continuous from the central portion of the 50 bolster to its ends,—the cross sectional curvature of the tension member being of substantially constant radius from end to end.

The bolster is preferably made of cast steel

and at each outer tapering end portion 6 has a spring seat cast integrally therewith, said 55 seat presenting a flat horizontal surface to the upper ends of the truck spring and being reinforced by vertical webs 7 disposed at the side edges of the seat 5 and bolster end and said seat is furthermore reinforced by webs 8 60 at points near the center thereof, as clearly shown in Fig. 2.

In the construction shown in Fig. 4, the spring seat member 9 is made as a separate casting and is interengaged by means of a lug 65 10 on said member entering a socket 11 formed in the bolster,—said spring seat member 9 having a concave top web 12 to fit against the convex under side of the portion 6 of the bolster and extend to the top of the 70 same.

In the embodiment of the invention shown in Figs. 5 and 6, a bolster 13 of the built-up type is employed, and the same is made tapering from its central portion to its ends. 75 The tension member 14 has a transverse curvature which is of substantially constant radius throughout the length of the member. Flanges 15 extend along the top edges of the bolster and a top plate 16 is secured upon 80 said flanges, said plate being dished as at 17 and turned down at its outer end as at 18, the portion 18 fitting within the tension member and secured thereto by fastening means 19.

A spring seat member 20 (preferably a 85 casting) is provided at each end portion of the bolster and made with an upper curved face to conform to the convex face of the tapering end portion 21 of the bolster, the bottom surface of the member 20 being horizontal for the accommodation of springs. The member or casting 20 may be reinforced by side webs 22 and intermediate webs 23. The seat member or casting 20 is interengaged with the tension member of the bolster 90 through the medium of a lug 24 projecting from said seat member and entering a socket or spring 25 in the bottom portion of said tension member.

Having fully described my invention what 100 I claim as new and desire to secure by Letters-Patent, is:—

1. A truck bolster made tapering from its central portion to its respective ends, the tension member of the bolster being arcuate from 105 its central portion to its ends, and provided

at each end with a spring seat member having a horizontal lower face and vertical longitudinal webs reinforcing the sides and intermediate portions of said spring seat member and extending between said member and the tension member of the bolster.

2. A hollow truck bolster having a tension portion of arcuate cross section, a separate spring seat member applied to and conforming with the contour of each end portion of the bolster and having interengaging connection with the latter.

3. A hollow truck bolster made tapering from its central portion to its ends and having an arcuate cross section, and a separate spring seat member conforming to the contour of each tapering and arcuate end portion of the bolster and having interengaging connection therewith.

4. A hollow truck bolster made tapering from its central portion to its ends and having an arcuate cross section, each tapering end portion having a socket, a separate spring seat member conforming to the contour of

each end portion of the bolster and having a lug to enter said socket.

5. A truck bolster comprising a tension member made tapering from the central portion of the bolster to its ends, said member having arcuate cross section, and a top member secured over said tension member, end portions of said top member entering the tension member and secured to end portions thereof.

6. A truck bolster comprising a tension member made tapering from the central portion of the bolster to its ends, said member having arcuate cross section, a top member secured over said tension member, end portions of said top member entering the tension member and secured to end portions thereof, and a separate spring seat member engaged with each end portion of the tension member of the bolster.

In testimony whereof, I have signed this specification.

HARRY W. STERTZBACH.
